United States Patent Office

Des. 179,446
Patented Dec. 25, 1956

179,446

FRUIT DISH

Orville C. Hamon, Cedars, Okla.

Application August 10, 1956, Serial No. 42,577

Term of patent 14 years

(Cl. D36—2)

FIG.1

I claim:

The ornamental design for a fruit dish, as shown.
